UNITED STATES PATENT OFFICE.

THEODORE W. KLOMAN, OF BAYONNE, NEW JERSEY.

DESIGN FOR A PUZZLE.

SPECIFICATION forming part of Design No. 26,317, dated November 24, 1896.

Application filed September 18, 1896. Serial No. 606,302. Term of patent 3¹ years.

To all whom it may concern

Be it known that I, THEODORE W. KLOMAN, of Bayonne, (Bergen Point,) Hudson county, New Jersey, have invented and produced a new and original Design for a Puzzle, of which the following is a specification, reference being had to the accompanying drawing, which represents a plan of my newly-designed puzzle.

10 The leading feature of my design consists of a series of irregular blocks having arched sides and which jointly form a continuous disk.

The numerals 1 to 16 represent a series of

blocks which are bound by arched sides, and 15 of which the blocks 2 3 4 5 7 8 10 11 12 14 15 are triangular, blocks 1 6 13 are quadrangular, and the block 9 is five-sided. The blocks 1 to 16, when assembled as shown, form a continuous disk.

20 What I claim is—

The design for a puzzle, substantially as herein shown and described.

THEODORE W. KLOMAN.
